UNITED STATES PATENT OFFICE.

GEORGE HOFMANN, JR., AND AUSTIN D. HOFFMAN, OF CHICAGO, ILL.

FIRE-ESCAPE.

SPECIFICATION forming part of Letters Patent No. 276,585, dated May 1, 1883.

Application filed February 14, 1883. (No model.)

To all whom it may concern:

Be it known that we, GEORGE HOFMANN, Jr., and AUSTIN D. HOFFMAN, of Chicago, in the county of Cook and State of Illinois, have invented new and useful Improvements in Fire-Escapes, of which the following is a specification, reference being had to the accompanying drawings, illustrating the improvement, in which—

10 Figure 1 is a perspective representation of a fire-escape embodying our improvement; Fig. 2, a sectional elevation of the lower end of one brace-standard enlarged, more clearly to show the construction; Fig. 3, an enlarged section of the top end of one brace-standard, showing the acorn-cap. Fig. 4 shows another kind of netting from that supported by the brace-standards.

The present invention relates to those escapes which are employed for catching people leaping from burning buildings.

20 The nature of the invention consists of a portable frame, which, by means of bracing-standards and stretching-ropes, is made to support a netting or canvas of suitable strength and elasticity to sustain the strain of a person or persons leaping from different heights of a building, as the whole is hereinafter fully described and shown.

30 A B e represent a frame, which is preferably made of light strong wood, or of wood and iron.

C represents what we term "bracing-standards," which also may be made of wood. Their lower ends are, close to the middle frame-piece, A, pivoted by means of ball-and-socket joints c d E, so as to have a free movement from vertical positions to angles of about forty-five degrees, (45°). The tops of the bracing-standards are provided with acorn-caps b b b, for the convenience of attaching the corners of the canvas or netting F and the tightening-ropes a a a a. These ropes, by means of intermediate pulley-blocks D, are attached to the ends of the outer frame-pieces, A A, as shown at Fig. 1, in order that the netting or fabric F may be brought to the required tension in a speedy manner by persons of ordinary skill.

In practice the frame may be constructed to support a netting or canvas ten by twenty or 50 ten by thirty feet, and the bracing-standards may be formed to raise the netting ten or twelve feet from the ground or place on which the frame stands.

Where the sidewalk is not so broad as the 55 frame A B e is, the latter can be quickly supported at one side by a block on the street, should the latter be much below the walk.

As a means to get desirable results from the apparatus fire departments should be provided with a suitable number, to be transported on a truck, which is provided with ways for sliding them up to a building in the shortest period of time, or otherwise placing them in convenient positions for persons to 65 leap thereon.

Buildings in which a large number of persons stay should be provided with one or more of these fire-escapes convenient for use.

Where room is a consideration, the standards C may be constructed to lie flat on the frame A B e, and the netting may be stored where it can be had without delay.

By experiments we find that four men can carry from any convenient place the frame, and set the apparatus in so short a time as to meet any, even unusual, emergency. Where there is greater ease required than the elasticity of the netting, the ropes a a a may be provided with elastic attachments of rubber; and to attain a greater bracing support the lower ends of the braces C may be placed on opposite sides of the middle frame-piece, A.

We claim as new and desire to secure by Letters Patent—

85 The frame A B e of a fire-escape, constructed substantially as specified and shown, with the bracing-standards C C C C, pivoted thereto in inclined positions, as shown, in combination with the netting or canvas F and tightening-ropes a a a a, as and for the purpose specified.

GEORGE HOFMANN, JR.

AUSTIN D. HOFFMAN.
